UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

DRAFT RIGGING

Application filed September 13, 1928. Serial No. 305,817.

This invention relates to draft rigging and more particularly to spring and friction draft gears adapted for use on railway cars.

The principal object of my invention, generally considered, is the adaptation of such cushioning mechanism as Cardwell friction draft gears which are ordinarily used with vertical yokes and one key for use with a second key and associated front follower. 10 Another object of my invention is to provide a combined front follower and draft gear housing which is adapted for use with Cardwell and other similar types of draft gears.

15 A further object of my invention is to provide railway draft rigging involving a vertical hooded yoke, the hooded portion of which embraces the front end of the associated draft gear or cushioning mechanism 20 which is preferably formed as a combined front follower and housing.

A still further object of my invention is the provision of a combined front follower and housing casting, the side walls of the 25 rearmost portion of which are spaced to correspond with the distance between associated draft sills, the forward portions of said side walls converging toward one another for reception between the side walls of the hood of 30 an associated yoke.

Other objects and advantages of the invention relating to the particular arrangement and construction of the various parts will become apparent as the description 35 proceeds.

Referring to the drawings illustrating my invention, the scope whereof is defined by the appended claims:

Figure 1 is a plan, shown partly in horizontal section, of a portion of the underframe of a car with associated draft rigging embodying my invention.

Figure 2 is a vertical longitudinal sectional view of the underframe and rigging 45 shown in Figure 1, portions of the draft gear housings and yoke being shown in side elevation.

Figure 3 is a fragmentary view corresponding to Figure 2, but showing a modification.

50 Referring to the drawings in detail, like

parts being designated by like reference characters, and first considering the embodiment of my invention illustrated in Figures 1 and 2, a portion of an underframe is illustrated adapted for use on cars or other railway rolling stock, said underframe comprising side sills 1 connected at their ends by combined striking and sill tie castings 2 and at their intermediate portions by bolster center filler and backstop castings 3. In 55 the present embodiment the combined casting 2 at each end of the gear is formed with rearwardly extending flanges or webs 4 attached to the draft sill webs and slotted as at 5 to form in effect the forward portions 60 of cheek plates. Said cheek plate portions are preferably continued by castings 6 attached to the webs of the side sills in any desired manner, as by rivets 7, said castings completing the slotted portions 5 by having 65 forwardly opening slots 8 therein and also preferably provided with rear or second slots 9. As is usual, the top flanges of the sills 1 are desirably connected by a cover plate 10. 75

Received between the sills 1 is draft rigging involving a coupler 11, the shank of which is illustrated with a swivel block 12 pivotally connected thereto as by means of a pivot pin 13 so that horizontal angling between the butt and stem is permitted. Said coupler is connected with a vertical yoke 14, for simultaneous, although not necessarily coextensive longitudinal movement, by means of a horizontal key 15 which extends through 80 corresponding slots in the shank of the coupler and the side walls 16 of the hooded front end 17 of said yoke. The ends of said draft key are extended and received in the slots 5 and 7 of the striking casting and 85 cheek plates as illustrated.

Received between the arms of the yoke 14 and normally engaging the butt or swivel block 12 of the coupler 11 is draft gear or cushioning mechanism 18. Said mechanism 95 in the present embodiment is illustrated as Cardwell friction draft gear but it will be understood that I do not wish to be limited to this showing. Said gear involves a forward housing or casing 19 and a rear housing 100

or casing 20, said housings opening toward each other and receiving friction elements generally designated by the reference character 21. It will be seen that the front housing 19 has a transverse web or wall 22 and top, bottom and side walls extending rearwardly therefrom or toward the other housing 20. Said walls are also extended forwardly of the web or wall 22 and preferably joined by a transverse web or wall 23. The rear housing is preferably similarly formed and its second or rearmost transverse wall or web 24 in the present embodiment forms the rear wall thereof and is normally engaged by the yoke 14 and the sides thereof are engaged by the stop portions 25 on the backstop casting 3, said stops being preferably spaced to receive the rear end of the yoke 14 therebetween.

The front housing 19 is, in the present embodiment, formed as a combined front follower and housing and for that purpose the side walls thereof at and forwardly of the intermediate web 23 are caused to converge toward one another from a distance corresponding with the distance between the sills 1 to a distance corresponding with the distance between the side walls 16 of the hooded portion 17 of the yoke so that the front end of said housing is normally received between the side walls of said yoke. The side walls of the housing 19 are at their forward ends joined by a front wall 26 which is adapted to engage the rear wall of the swivel block 12, as illustrated. The side walls of the front housing 19 are preferably formed with horizontal slots 27 receiving a rear or second key 28 which extends through the slots 9 in the cheek plates and is adapted to connect said housing and associated cushioning mechanism with the cheek plates and sills of the car. Instead of having the intermediate wall 23 extend the full height of the front housing 19 like the wall 24 of the rear housing 20, said wall may be curved around the key 28, as illustrated particularly in Figure 2 and be joined to the front wall 26 by a pair of walls 29, the front portion of said wall 23 being preferably joined with the web 22 by the horizontal rigidifying wall 30 which preferably lies on the line of draft of the gear or midway between the upper and lower walls of the housing thereof.

Inasmuch as a Cardwell friction draft gear is illustrated in the present embodiment, the sides of the housings or casings 19 and 20 between the transverse webs 22 thereof are slotted or notched, as indicated at 31, for permitting the passage of the transverse rods 32 upon which are applied the resilient means 33 which cause the friction elements of the gear to always remain in engagement. The rear housing 20 of the gear is, in the present embodiment, illustrated as supported by the lower arm of the yoke 14,

which is in turn supported by a tie or carrier iron 34 connected with the lower flanges of the associated sills by bolts or the like 35. The front end of the yoke, as will be understood, is supported by the front key 15, and the front casing or housing 19 is supported by said yoke and the second key 28 is also adapted to support said housing 19 or the front end thereof if necessary.

Referring now to the embodiment of my invention illustrated in Figure 3, a construction is there disclosed identical with the first embodiment, except that the front follower portion 36 is formed separate from the associated cushioning mechanism 18^a which is only diagrammatically illustrated, that is, a front follower which may correspond with a front follower such as is normally used with Farlow draft rigging, may be inserted between the rear end of the coupler shank 11^a or swivel block 12^a thereon and the front face of the foremost housing or casing of the cushioning mechanism 18^a rather than having said casing extended and formed as an integral follower portion as in the first embodiment. Except as specifically described, the present embodiment may correspond with that of the first embodiment.

From the foregoing description, taken in connection with the accompanying drawings, it will be seen that I have devised draft rigging for railway cars in which the front housing of associated friction draft gear is either modified to act as a front follower with an associated second key or is adapted to engage a standard front follower for the transmission of forces between an associated coupler and such gear. When the draft gear front housing is modified to also act as a front follower, the side walls thereof are preferably formed to converge toward one another so that the front end of the combined casting is adapted to fit between the side walls of the hooded end of an associated yoke, the rearmost parts of the side walls of said casting being desirably spaced to correspond with the spacing between the associated draft sills. The housings or casings are preferably so formed that the distance between adjacent portions thereof when the gear is released corresponds with the gear travel so that when compressed the housings or walls thereof engage and enclose the friction elements.

Having thus described my invention, I claim:

1. In railway draft rigging, in combination, a coupler with a rearwardly extending stem, a vertical yoke with side walls connecting the forward portions thereof and normally lying on either side of said stem, means connecting said coupler and yoke for simultaneous rearward movement, cushioning mechanism embraced by said yoke and with a forward portion normally received between the side walls of said yoke and engaging the

rear end of said stem, and means passing through said mechanism for connecting it to associated draft sills.

2. In railway draft rigging, in combination with draft sills, a coupler with a stem, a hooded vertical yoke, a draft key connecting said coupler and yoke for simultaneous rearward movement, cushioning mechanism embraced by said yoke and provided with a forward portion engaging the stem of said coupler between the side walls of the hooded portion of said yoke, said mechanism comprising housings enclosing friction elements, and a draft key connecting the foremost housing to said sills.

3. In railway draft rigging, in combination, a coupler with a stem, a hooded vertical yoke normally receiving said stem in the hooded portion thereof, a draft key connecting said coupler and yoke for simultaneous rearward movement, cushioning mechanism embraced by said yoke and involving a forward member acting as a front follower, said forward member normally engaging the stem of said coupler in the hooded portion of said yoke, and slotted for receiving a second draft key.

4. In railway draft rigging, in combination with draft sills, a coupler with a stem, a yoke having a hooded forward end, a draft key connecting said coupler and yoke for simultaneous rearward movement, cushioning mechanism embraced by said yoke and comprising a pair of casings with pockets opening toward each other for receiving friction elements, the sides of said casings being spaced so as to normally lie close to said sills for guiding purposes, the forward end of the forward casing being decreased in width and normally received in the hooded portion of said yoke in engagement with the stem of said coupler.

5. In railway draft rigging, in combination with sills, a coupler with a rearwardly extending stem, a yoke with a hooded forward portion normally receiving said stem, a draft key connecting said coupler and yoke for simultaneous rearward movement, cushioning mechanism embraced by said yoke and comprising a housing portion the forward end of which is normally received in the hooded portion of said yoke in engagement with said coupler stem and the rearward portion of which is of greater width so as to lie close to the associated sills for guiding purposes.

In testimony whereof I affix my signature.
DONALD S. BARROWS.
